CLAIM

The ornamental design for an adaptive wrap top, as shown and described.

DESCRIPTION

FIG. 1 is an exterior view of an adaptive wrap top shown in an open position showing my new design;

FIG. 2 is a front elevational view of the adaptive wrap top shown in a configuration of use;

FIG. 3 is a side elevational view thereof;

FIG. 4 is a back elevational view thereof; and,

FIG. 5 is an interior view of the adaptive wrap top shown in an open position.

The broken line outline of the partial human figure in FIGS. 2-4 assist in illustrating how the adaptive wrap top may appear when in position of use, but forms not part of the claimed design. The broken lines along the surface of the adaptive wrap top depict features thereof that form no part of the claimed design.
